UNITED STATES PATENT OFFICE.

CHARLES C. LAURITSEN, OF CLEVELAND, OHIO, ASSIGNOR TO THE OHIO BODY & BLOWER COMPANY, OF CLEVELAND, OHIO, A CORPORATION OF OHIO.

VALVE.

1,397,591.

Specification of Letters Patent. Patented Nov. 22, 1921.

Application filed April 12, 1920. Serial No. 373,301.

To all whom it may concern:

Be it known that I, CHARLES C. LAURITSEN, a subject of King of Denmark, residing at Cleveland, in the county of Cuyahoga and 5 State of Ohio, have invented a certain new and useful Improvement in Valves, of which the following is a full, clear, and exact description, reference being had to the accompanying drawings.

10 This invention relates to an improved self-acting valve that is adapted to automatically control the supply of liquid to a tank, reservoir or the like; and its objects are to provide a highly efficient device of 15 this character, yet one that is simple of construction; economical and convenient of manufacture; is durable, obviating the need of piston packing; which acts with a cushioning effect at the end of its stroke, avoiding 20 injury to the valve seat by pounding; is positive of operation; is not likely to get out of order; and which lends itself readily to various installations.

An embodiment of my invention through 25 which the foregoing objects are attained is illustrated in the drawing accompanying and forming a part hereof, and wherein Figure 1 shows a section through the valve; and Figs. 2 and 3 installations thereof, the 30 latter illustrating a modification of the valve.

Referring to the drawing by the use of 35 reference characters, 1 is the valve casing that is divided into inlet and outlet compartments 2 and 3, respectively, by a partition 4 containing a valve seat 5. The valve seat, in the present instance, is incorporated 40 in a spider that is screwed into an aperture of the partition and has a central guide 6 spaced from its rim by radial arms 7.

Operating within the guide 6 is the tubular stem 10 of a valve element 11 involving the valve disk 12 and piston 13. The valve disk is shown as having a tapered seating 45 portion corresponding in angle with the co-operating part of the valve seat 5 and it is of lesser diameter than the opposed circular face of the piston 13 which is spaced a suitable distance from the valve disk along 50 the stem 11, the parts having strengthening ribs 14 disposed between them. The piston 13 operates within a cylinder 15 formed in the upper end of the casing 1 and in axial alinement with the valve seat. The outer 55 end of the cylinder is closed by a cover plate

16 that may be secured by any suitable means to the casing. A passageway 18 is formed in a thickened portion of the wall of cylinder 15 and communicates with the cylinder in the vicinity of its inner and outer ends, the outer end of the cylinder being shown as of somewhat greater diameter than the portion within which the piston 13 is guided. It will be observed 60 that the lower end of the passageway 18 enters the cylinder immediately adjacent the latter's inner end so that the passageway is uncovered upon a slight outward movement of the piston from its innermost position. And it may be explained, further, 65 that the piston fits the cylinder loosely enough to permit of a slight leakage past the piston from the inlet chamber of the casing.

A threaded boss 19, onto which a perforated cap 20 is screwed, projects outwardly beyond the circular wall of the piston 13 and constitutes, in effect, an extension of stem 10; and confined within the cap for movement toward and from its seat is an 70 auxiliary or pilot valve 25 having a stem 26 that is guided within the bore of the tubular stem 10, the stem 26 being fluted at 75 to avoid obstruction of flow through the bore of the former stem when valve 25 is 80 lifted off its seat.

A pipe 30 has one of its ends screwed through a tapped hole in the wall of casing 1 opposite, and in axial alinement with, the cylinder 15, and stem 26 is shown as projecting 85 into the pipe. The lower end of the pipe is threaded for the application of a cap 31, equipped with a packing gland 32 for preventing leakage about a rod 33 that is guided through a hollow boss 34 onto which 90 the gland nut is threaded. The rod 33 is connected to the pilot valve stem 26 through a tube 35 which is slipped over the rod and stem and connected thereto by pins 37.

The rod 33 is pivoted to a lever 38 which 95 has its fulcrum in the lower end of a link 39 that is swung from an arm 40 projecting from the side of the cap 31. A float 41 is carried by the outer end of the lever 38.

In Fig. 2 I have shown my improved valve 100 in a pipe or conduit 42 which supplies liquid to a system including a filter 43 and a tank 44, the tank having an outlet 45. The float mechanism is situated within the tank and serves through its connection with the valve 110

to maintain the liquid level in the tank substantially constant. In operation, when the liquid falls below a predetermined level the float 41 descends and rocks lever 38 in a direction to lift the pilot or auxiliary valve 25 off its seat, permitting the liquid in cylinder 15 to escape through the tubular valve stem 10 to the outlet chamber 3 of the casing. Thereupon the line pressure within 10 the inlet chamber 2, acting upon the piston 13, lifts the valve disk 12 from its seat. A flow of liquid is now established through conduit 42 and it continues until the liquid level within the tank 44 rises sufficiently to 15 elevate the float and draw downward on the rod 33, and parts connected therewith, and seat the valve 25. As soon as this valve is seated and the escape of liquid from the cylinder 15 is cut off, the pressure, communicated to the cylinder from the inlet chamber 2 through the passageway 18, builds up rapidly within the cylinder and forces the piston in a direction to seat the valve disk 12. As the disk approaches its seat, 20 the speed of the piston is materially retarded by reason of its closing the inner end of the passageway 18 and making the further supply of liquid to the cylinder 15 dependent upon the escape of the liquid past the piston. This course being quite restricted and the passage of liquid therethrough comparatively slow, the movement of the piston at this stage in its operation is correspondingly sluggish and as a consequence the valve is gently lowered to its seat. 25

From the foregoing description it will be obvious to those skilled in the art that my invention is applicable to numerous situations, the installation just described being 30 only one example of its use. Another example, and one which allows of a slight change in the valve design, is shown in Fig. 3. Here the float mechanism is situated within the receiver 46 into which the conduit 45 42^a discharges directly. Consequently there would be no object in preventing leakage from the valve to the receiver, so that not only may the packing gland 32 be omitted, but a larger pipe 30^a may be substituted for 40 the former pipe 30, the valve casing communicating directly therethrough with the receiver, obviating the need of further pipe and converting, in the present instance, the valve casing 1 from a straight to an L connection. 50

Attention is particularly directed to the manner in which the float mechanism is connected to the casing 1 and to the stem of the auxiliary or pilot valve 25. Inasmuch as 60 these connections are accomplished through the use of standard pipe and tubing, represented herein by the elements 30 or 30^a and 35, it is evident that to alter the distance between the valve casing and float mechanism requires only the substitution of ap-

propriate lengths of pipe and tubing, and these can be readily obtained in any desired lengths, and threaded and perforated for the purpose, with little trouble and at slight expense. 70

Having thus described my invention, what I claim is:

1. In a valve of the character set forth, the combination of a casing divided into an inlet and an outlet compartment by a partition having an opening surrounded by a valve seat, the casing involving a cylinder opening into the inlet compartment, there being a passageway through which the inlet compartment communicates with the outer 80 end of the cylinder when the hereinafter mentioned piston is at any but its innermost position, a piston within the cylinder, a valve element for coöperation with the valve seat and having operative connection with the piston so as to move in unison therewith, the piston having a greater area exposed to the inlet compartment than has the valve element, and means governing the escape of fluid from the cylinder. 90

2. In a valve of the character set forth, the combination of a casing divided into an inlet and an outlet compartment by a partition having an opening surrounded by a valve seat, the casing involving a cylinder 95 opening into the inlet compartment and a passageway through which the opposite ends of the cylinders communicate, a piston within the cylinder, a valve element for coöperation with the valve seat and having operative connection with the piston so as to move in unison therewith, the parts being so designed that when the valve element is on its seat, the piston closes the aforesaid passageway from direct communication with the 105 inlet compartment, the piston having a greater area exposed to the inlet compartment than has the valve element, and means governing the escape of fluid from the cylinder. 110

3. In a valve of the character set forth, the combination of a casing divided into an inlet and an outlet compartment by a partition having an opening surrounded by a valve seat, the casing involving a cylinder opening into the inlet compartment, a piston within the cylinder, a valve element for coöperation with the valve seat and having operative connection with the piston so as to move in unison therewith, the piston having a greater area exposed to the inlet compartment than has the valve element, there being a by-pass through which the outer end of the cylinder communicates with the inlet compartment and which is closed from 115 direct communication with the inlet compartment when the valve element is on its seat, and means governing the escape of fluid from the cylinder. 125

4. In a valve of the character set forth, 130

the combination of a casing divided into an inlet and an outlet compartment by a partition having an opening surrounded by a valve seat and incorporating a cylinder that 5 opens into the inlet compartment and is in axial alinement with the valve seat, a member incorporating a piston that operates within the cylinder and a valve element for coöperation with the seat, the piston and 10 valve element being connected together and spaced apart by a tubular stem which opens beyond each the piston and valve element, an auxiliary valve for closing the bore of the tubular stem and having a stem extending 15 through said bore, the casing having an opening in its wall through which access may be had to the last mentioned stem, a tubular extension applied to the casing in register with said opening, a fitting applied 20 to the opposite end of the extension, a rod guided within said fitting, a sleeve fitting over and connecting the stem of the auxiliary valve and said rod, and float mechanism operatively connected with the rod.

25 5. In a valve of the character set forth, the combination of a casing divided into an inlet and an outlet compartment by a partition having an opening surrounded by a valve seat and incorporating a cylinder that 30 opens into the inlet compartment and is in axial alinement with the valve seat, a member incorporating a piston that operates within the cylinder and a valve element for coöperation with the seat, the piston and 35 valve element being connected together and spaced apart by a tubular stem which opens beyond each the piston and valve element, an auxiliary valve for closing the bore of the tubular stem and having a stem extending 40 through said bore, the casing having an opening in its wall through which access may be had to the last mentioned stem, a tubular extension applied to the casing in register with said opening, a fitting applied 45 to the opposite end of the extension, a rod guided within said fitting, a sleeve fitting over and connecting the stem of the auxiliary valve and said rod, and float mechanism carried by the fitting and operatively connected with the rod.

6. In a valve of the character set forth, the combination of a casing divided into an inlet and an outlet compartment by a partition having an opening surrounded by a valve seat and involving a cylinder opening 55 into the inlet compartment in axial alinement with a valve seat, a member incorporating a piston which operates within the cylinder and a valve element for co-operation with the seat, the piston and the 60 valve element being connected and spaced apart by a tubular stem the bore whereof opens beyond each the piston and the valve element, the piston having a greater area exposed to the inlet compartment than has 65 the valve element, an auxiliary valve for closing the bore of the tubular stem beyond the piston and having itself a stem which extends through the bore of the tubular stem, the casing having an aperture in axial 70 alinement with the cylinder and valve seat, a pipe having one of its ends fitted within the aperture of the casing, a cap applied to the opposite end of the pipe and having a guide opening, a rod reciprocable within 75 said opening, means connecting the rod and the last mentioned valve stem, a float lever suspended from the cap and having a part operatively connected to the rod, and a float carried by the lever, there being 80 means for supplying fluid to the cylinder.

7. In a device of the character set forth, the combination of a valve casing divided into an inlet and an outlet compartment, a main valve arranged to close communication between said compartments, means actuated by fluid from the inlet compartment for closing the main valve, a pilot valve for releasing said fluid and allowing the main valve to open, a conduit communicatively connected with the outlet compartment and into which the outlet compartment may discharge, float mechanism, and means extending throughout said conduit and operatively connecting the float mechanism with the pilot valve.

In testimony whereof, I hereunto affix my signature.

CHARLES C. LAURITSEN.
